R. D. WORK

PROPULSION MECHANISM FOR DIRIGIBLES, AIRSHIPS, AND SIMILAR DEVICES

Filed Aug. 29, 1922

UNITED STATES PATENT OFFICE.

ROBERT D. WORK, OF PHILADELPHIA, PENNSYLVANIA.

PROPELLUTION MECHANISM FOR DIRIGIBLES, AIRSHIPS, AND SIMILAR DEVICES.

Application filed August 29, 1922. Serial No. 584,942.

To all whom it may concern:

Be it known that I, ROBERT D. WORK, a citizen of the United States, residing at Philadelphia, county of Philadelphia, State 5 of Pennsylvania, have invented a new and useful Propulsion Mechanism for Dirigibles, Airships, and Similar Devices, of which the following is a specification.

My present invention relates to propulsion 10 mechanism for dirigibles, air ships and similar devices wherein the propulsion can be obtained by means of one or more air driven vanes operatively connected with the propeller, or the propeller may be actuated 15 by the operator as may be desired.

Another object in view is to devise novel means for varying the effective wing area of the vanes.

With the above and other objects in view 20 which will hereinafter more fully appear, my invention comprehends a novel construction and arrangement of propulsion mechanism for dirigibles, air ships and similar devices.

25 It further comprehends a novel construction and arrangement of vanes, each vane being made up of a plurality of smaller vanes which can be adjusted as may be desired by the operator, the main vanes being 30 operatively connected with the propeller to drive it and means being also provided to disconnect the operative connection between the main vanes and the propeller and to connect the propeller with a pedal actuated shaft actuated by the operator.

35 Other novel features of construction and advantage will hereinafter more fully appear in the detailed description and the appended claims.

40 For the purpose of illustrating my invention, I have shown in the accompanying drawings an embodiment thereof which is at present preferred by me, since this embodiment will give in practice satisfactory 45 and reliable results. It is, however, to be understood that the various instrumentalities of which my invention consists can be variously arranged and organized and that my invention is not limited to the precise 50 arrangement and organization of these instrumentalities as herein shown and described.

Figure 1 represents a top plan view of a

dirigible or air ship in conjunction with which propulsion mechanism, embodying 55 my invention, is employed.

Figure 2 represents a side elevation partly in section of the construction seen in Figure 1.

Figure 3 represents a fragmentary view 60 showing more particularly the vane construction.

Figure 4 represents a sectional view showing a portion of the vane controlling mechanism and certain of its adjuncts. 65

Figure 5 and 6 represent detail views showing a vane shutter and certain of its adjuncts in different positions.

Similar numerals of reference indicate 70 corresponding parts.

Referring to the drawings.

1 designates the skeleton framework within which is contained, in the usual manner, a plurality of inflatable gas bags. The frame 1 has connected to it a car 2 in which 75 is mounted a propeller shaft 3 having connected to it a propeller 4. The gas bags are designated 5. The propeller shaft 3 has mounted thereon a gear 6 which is adapted to mesh with a gear 7 carried by a shaft 8 80 which is vertically disposed and extends through the framework 1. The shaft 8 is mounted in a sleeve 9. A clutch 10 is provided by means of which the gear 7 may be moved into or out of mesh with the gear 6. 85 The shaft 8 at its upper end, see more particularly Figure 4, has fixed to it a hub 11, to which is connected the arms 12, which latter carry the vanes 13. These vanes 13, as illustrated, are shown as consisting of a 90 rectangular framework in which is pivoted a series of shutters 14, the shutters being pivoted near their upper end, as at 15, see Figure 3.

The side bars of each vane are provided 95 with the slots 16 through which extend rods 17, said rods being connected to the actuating bars 18. These actuating bars 18 have connected to them the cables 19 which pass over the pulley 20, and these cables 19, see 100 Figure 4, are connected to a sleeve 21 rotatable on the sleeve 9. A collar 22 is keyed to the sleeve 9 and the sleeve 21 is freely rotatable with respect to the collar 22 but moves upwardly and downwardly with it. 105 A spring 23 is interposed between the collar

22 and the fixed washer 24, so that the tendency of this spring is to move the collar 22 upwardly and thereby permit the shutters 14 to close to a predetermined degree, this movement being assisted by the spring 25 connected to the bars 18. The collar 22 is connected by means of a cable 26 with a manually controlled drum 27. The car 2 is provided with a seat 28 for the operator and in proximity to this seat is a wheel 29 operatively connected with the rudder 30 to actuate it. The propellor shaft 3 is connected by means of a manually controlled clutch 31 with a shaft 32 which latter carries the gear 33 meshing with a gear 34 through which is operatively connected the foot pedals 35. Each vane shutter 14 has its opening movement limited by a stop 36.

In some cases, it is desirable to employ stabilizers 37 in the form of wings having any desired or conventional shape movably connected with the skeleton framework 1 and controlled and operated by means of rods 38 and controlling mechanism 39 of any desired construction. It will thus be seen that the position of these stabilizers can be adjusted. I may also employ, if desired, a level adjusting vane 40 connected with a lever to which is connected a cable 41 which lever in turn is connected to a bell crank being controlled by means of a rod 43 secured to a lever 44 in a position accessible to the operator. By the operation of this lever 44, the vane 40 may be turned upwardly or downwardly in order to cause the forward end of the air ship to descend or ascend as may be desired.

The operation of my novel propulsion mechanism will now be readily apparent and is as follows:

If the operator desires to have the dirigible air ship or similar device automatically propelled due to the action of the wind on the vanes 13, the clutch 31 is moved into its declutched position and the clutch 10 is moved into its clutched position so that the gears 6 and 7 are in mesh. The operator, actuating the drum or hand wheel 27 in a direction to draw down the collar 22, will thereby exert a pull on the cables 19 and move the actuating bars 18 downwardly against the action of the spring 25.

The rods 17, if desired, may be rubber coated or coated with any desired material which acts as a shock absorbing element. It will thus be seen that the closing movement of the shutters 14 can be limited as desired so as to vary the resistance offered by such shutters to the wind.

The wind acting against the vanes causes the shaft 8 to revolve and thereby the propellor 4 to which it is operatively connected.

If the operator desires to drive the dirigible by means of the foot pedals 35, the clutch mechanism 10 is actuated to move

the gear 7 out of engagement with the gear 6, and the clutch 31 is moved into clutched position, so that when the gear 34 is revolved, due to the operator actuating the foot pedals 35, the propeller shaft 3 and its propellor 4 will be driven, as is apparent.

When a main vane 13 revolves and during its revolution is brought into the face of the wind, the vanes 14 can open, the opening movement of the vane shutters 14 being limited by the stops 36, so that at such time the wind can blow through the openings in the main vane.

In so far as I am aware, I am the first in the art to employ wind driven vanes positioned above the gas balloon which are operatively connected with the propeller to drive it, and to provide means whereby the effective wing area of the vane can be adjusted, and wherein provision is made to have the vane shutters open when a vane comes into the face of the wind.

For the purpose of illustration, I have shown six vanes but it will be apparent that one or more may be employed, as may be desired.

It will now be apparent that I have devised a new and useful dirigible, air ship and similar device which embodies the features of advantage enumerated as desirable in the statement of the invention and the above description, and while I have, in the present instance, shown and described an embodiment thereof which will give in practice satisfactory and reliable results, it is to be understood that this embodiment is susceptible of modification in various particulars without departing from the spirit or scope of the invention or sacrificing any of its advantages.

Having thus described my invention, what I claim as new and desire to secure by Letters Patent, is:

1. In apparatus of the character stated, a gas balloon, a car suspended therefrom, a propeller at the forward end of said car, a seat at the rear of the car facing said propeller, a shaft extended from the propeller toward said seat, a small gear wheel upon said shaft, a larger gear wheel in mesh with said propeller gear wheel, foot pedals carried by the larger of said gear wheels, a rudder arranged at the rear of the car, a steering wheel arranged adjacent said seat, means connecting said steering wheel and rudder, and a wind driven vane arranged above the balloon and operatively connected with said propeller shaft.

2. In apparatus of the character stated, a gas balloon, a car suspended therefrom, a propeller at the forward end of said car, a seat at the rear of the car facing said propeller, a shaft extended from the propeller toward said seat, a small gear wheel upon said shaft, a larger gear wheel in mesh with

said propeller gear wheel, foot pedals carried by the larger of said gear wheels, a rudder arranged at the rear of the car, a steering wheel arranged adjacent said seat, 5 means connecting said steering wheel and rudder, a wind driven vane arranged above the balloon and operatively connected with said propeller shaft, and means to vary the effective wing area of said vane.

ROBERT D. WORK.
